UNITED STATES PATENT OFFICE.

JOSEPH G. AUSTIN, OF CHICAGO, ILLINOIS.

HOISTING-MACHINE.

SPECIFICATION forming part of Letters Patent No. 224,322, dated February 10, 1880.
Application filed June 18, 1879.

To all whom it may concern:

Be it known that I, JOSEPH G. AUSTIN, of Chicago, in the county of Cook and State of Illinois, have invented a new and useful Improvement in Hoisting-Machines, of which the following is a specification, reference being had to the accompanying drawings, illustrating the improvement and made a part hereof, in which—

- 10 Figure 1 is an elevation of a hoisting-machine embodying my improvement; Fig. 2, a plan or top view of the locking devices and elevator-beam detached from the other devices and shown double the size of the same parts in Fig. 1; Fig. 3, an enlarged view of one of the slotted dogs removed from its guides, but showing its connection with the head of the draft-bar; Fig. 4, enlarged views of the guides to one dog, taken transversely to the dog which 15 operates therein; Fig. 5, an enlarged perspective view of the frame which supports and guides the draft-bar, and also is a support for the upper end of the spring which forces the dogs outward and into the notches of the rack.
- 20 The present invention relates to an improved safety-lock for hand or steam hoisting-machines, whereby if the hoisting-rope should break the elevator would be securely locked to the elevator-guides.
- 25 The particular improvement consists in slotted dogs pivoted to the head of the draw-bar and combined with guides to direct the dogs into notched racks, and with a spring and adjustable jam-nut, whereby the dogs may be 30 adjusted to notched racks after they may have become worn, or to racks standing a greater or less distance from the elevator proper.

The advantage of this combination is that the elevator is supported wholly on the adjustable nut, which controls the position of the dogs in relation to the racks, and that there is no greater force on the coil-spring when raising one weight than another.

My device differs from the elliptic spring, which straightens out to catch in the notches of the racks, in that the pitch of the dogs is not such as to cause them to crowd with too great force against the guides; but there is sufficient pitch to enable the dogs to hold the platform suspended, although the guides should to any ordinary amount spread.

A represents the lifting-beam of an ordinary hoisting-machine or elevator, and B are the elevator-guides. C C are the toothed or notched racks in which the locking device of the elevator is to catch in case that the hoisting-rope should break, all of which have the ordinary construction.

D represents a frame, which is a continuous piece of iron extending from the beam A far enough up to permit a coil-spring, E, to be placed within its walls, and also properly to guide the draft-bar F and support it in a vertical position, a hole being made through the top of the frame for said bar to pass.

The lower part of the frame D is provided with flanges G G, which, by means of connecting rods or bolts H H, fasten to a strong iron plate, I, which is placed flatwise under the lifting-beam A, and projects laterally over the sides, to permit the bolts H to pass through it. The bolts, fitting closely to the beam A, prevent the frame or plate from turning out of place.

The draft-bar F passes through the lifting-beam A, and also through the plate I, and on the lower end of the bar is formed a screw-thread, on which a jam-nut, J, is placed to sustain the weight of the elevator or platform.

Above the beam A is placed a nut, K, between which and the top of frame is placed a coil-spring, E, of such strength as will insure the instantaneous movement of the dogs outward should the hoisting-rope L break.

A socket-head, M, is formed on the upper end of the draft-bar F, and to it are pivoted dogs N N at P, the ends of which have bearings against said head, so that the pivots are not wholly relied on as supports against the pressure of the dogs endwise, as when engaging the racks. The middle portions of these dogs are provided with slots R, through which pins b from the guides S S pass, and not only act as fulcrums for the dogs to turn on to some extent, but permit the dogs to have a longitudinal movement, both of said movements being necessary to enable the dogs to enter the notches in the racks C C in case the cord or rope L should break. The outer guides, T T, not only direct the dogs at all times into the racks C C, but they prevent the dogs from springing or being bent up by any sudden jar they may be liable to.

The device is automatic in its operation as constructed. The only attention required is to turn up the nut J, so as to keep the outer ends of the dogs N N as close to the racks C C as possible, but not so as to enter the notches in the movement of the elevator or platform.

The object of that position of the dogs in relation to the rack is that the dogs shall move the shortest possible distance to catch in the notches of the rack in case the rope L should break.

I claim and desire to secure by Letters Patent—

The slotted dogs N N, having fulcrums and sliding movements on pins b, in combination 15 with guides S S, draft-bar and head F M, spring E, frame D, plate I, lifting-beam A, and set-nut J, and jam-nut K, as and for the purpose set forth.

JOSEPH G. AUSTIN.
